(57) **CLAIM**

(21) Appl. No.: **29/349,053**

The ornamental design for a motorcycle fairing radiator vent trim assembly, as shown and described.

(22) Filed: **Mar. 4, 2010**

(51) **LOC (9) Cl.** 12-11

DESCRIPTION

(52) **U.S. Cl.** D12/114

FIG. 1 is a perspective view of the motorcycle fairing radiator vent trim assembly of the present invention.

(58) **Field of Classification Search** D12/110, D12/114, 126, 190, 223, 163, 166, 172, 216; 180/219; 280/288.1–288.4; 296/187.01–187.03, 296/187.09, 187.12, 78.1, 95.1, 96.11, 1.07, 296/1.08

FIG. 2 is a front side elevation view thereof.

See application file for complete search history.

FIG. 3 is a rear side elevation view thereof.

(56) **References Cited**

FIG. 4 is a top view thereof.
